The ornamental design for a combined screwdriver and wrench, as shown and described.

DESCRIPTION

FIG. 1 is a perspective view of a combined screwdriver and wrench showing my new design;

FIG. 2 is a top plan view of FIG. 1, wherein the bottom plan view appears identical thereto;

FIG. 3 is a front elevational view of FIG. 1, wherein the rear view appears identical thereto;

FIG. 4 is a left-hand elevational view of FIG. 2 showing a flat head screwdriver;

FIG. 5 is a right-hand side elevational view of FIG. 2 showing a Phillips head screwdriver;

FIG. 6 is a top plan view of a modified embodiment of the combined screwdriver and wrench, wherein the bottom plan view appears identical thereto;

FIG. 7 is a top plan view of a second modified embodiment of the combined screwdriver and wrench, wherein the bottom plan view appears identical thereto; and,

FIG. 8 is a top plan view of a third modified embodiment of the combined screwdriver and wrench, wherein the bottom plan view appears identical thereto.

FIG. 2

FIG. 6

FIG. 7

FIG. 8
